UNITED STATES PATENT OFFICE.

AUGUST ROSENTHAL, OF WEST ALLIS, WISCONSIN, ASSIGNOR TO ROSENTHAL MANUFACTURING CO., OF WEST ALLIS, WISCONSIN.

GEAR CASING FOR CORN HUSKERS.

Application filed February 23, 1926. Serial No. 90,061.

This invention relates to improvements in corn huskers and more particularly to an improved gear casing for corn huskers.

In corn huskers in which a plurality of 5 rolls are provided, it is the practice as disclosed in my patent No. 1,531,758 granted March 31, 1925 to arrange these rolls in a downwardly slanting direction and to join them operatively at their lower ends by means 10 of a plurality of intermeshing gears. These gears are carried in a gear box.

In machines of this type, great difficulty is experienced in keeping the trash out of 15 the gear boxes so that the gears may freely run and retain the lubricant.

This invention is designed to overcome the above noted defects, and objects of such 20 invention are to provide a novel means of sealing the gears in the gear box and preventing entrance of trash, grit or other material however finely this material may be divided.

Further objects are to provide a construction which may be easily applied to husking 25 machines and which does not require a redesign of the machine.

An embodiment of the invention is shown in the accompanying drawings, in which:

Figure 1 is a view partly in section of 30 the lower portion of the husking rolls with the gear box cover removed.

Figure 2 is a sectional view on the line 2—2 of Figure 1.

Referring to the drawings, it will be seen 35 that the husking machine is provided with a frame work 1 to which the ears 2 of transverse members 3 are bolted. These transverse members 3 carry between them the bearings 4 for the trunnions 5 for the husking 40 rolls 6. One of the husking rolls is usually the driving roll as described in greater detail in my above noted patent. For example, the roll marked 6' in Figure 1 is the driving roll and its bearing is held 45 in place by means of bolts 7 which extend through the transverse members 3.

Means are provided for adjusting the lower ends of these rolls and such means may consist of pressure blocks 8 which are carried 50 in guides 9. The position of these pressure blocks is controlled by means of the set screws 10. These pressure blocks, therefore allow adjustment of the bearings with reference to each other to take up wear.

The trunnions 5 of the rolls extend into 55 a gear box 11 which is provided with ears 12 bolted to the frame work 1 of the machine. This gear box is provided with open-topped pockets 13 within each of which a pair of hardened discs 14 are positioned, and held 60 in place by means of a retaining bar 14'. These discs are the thrust bearings for the rounded ends of the trunnions 5 as clearly shown in Figure 2. The trunnions are provided with inter-meshing gears 15 positioned 65 within the gear box 11. Preferably the gear box is provided with a removable cover 16, and as disclosed in my above noted patent, a shield plate 17 extends from the top of the gear box to a position over the smooth ends 70 of the husking rolls.

In actual practice, it has been found that dust and grit and other foreign matter will work its way into the gear box and interfere with the smooth running of the gears. 75

This invention overcomes the defects noted above by providing a rubber cover plate or front plate 18 for the gear box. This plate is held between the bearings 4 of the rolls and the front face of the gear box. It is apertured to receive the trunnions 5 of the rolls and in no way interferes with the smooth and free running of the machine. However, it is to be particularly noted that this rubber plate 18 conforms to the portions with which it contacts and thus prevents any entrance of trash, grit or foreign material. Obviously, the rubber plate is made of sufficient thickness to give it the necessary strength, and in actual practice it has been found highly effective and serviceable. 85

The material actually used for this cover plate or front plate consists of a fabricated rubber sheet in which a fabric body is formed within the rubber somewhat analogous to the construction of ordinary garden hose. Obviously, the exact material or manner of making this plate may be varied provided, however, it has the requisite strength, providing the necessary flexibility and retaining its yielding characteristics. With a plate constructed as described above, it has been found that the material closes around the trunnions sufficiently to keep out the foreign material and prevent loss of lubricant without however causing undue friction or binding. It is to be particularly 95 100 105

noted that all of the trunnions are sealed by this simple expedient and that individual sealing of each trunnion is avoided. Attempts to seal gear boxes have heretofore been made, but they either employ ordinary bearings which are recognized as ineffectual in keeping out foreign material or else they provide some form of stuffing box with its necessary relatively complicated construction.

It will be seen that a novel form of gear box closer has been provided which has all the advantages of stuffing boxes with none of their defects. It is thus possible to secure the advantages of stuffing boxes by a simple and cheaply produced member in a novel and highly effective manner.

It has been found that this type of covering plate or front plate may be easily applied and will effectively prevent the entrance of grit and permit the retention of lubricant within the gear box.

It will be further noted that the pressure blocks may be adjusted to alter the relative position of the rolls, and yet the yielding and flexible plate 18 will accommodate this motion and still maintain a sealed joint between the trunnions and the plate. In other words, the plate will alter its shape slightly to accommodate adjustment of the bearings without causing any opening to occur in the gear box seal.

Although the invention has been described in considerable detail, such description is intended as illustrative rather than limiting as the invention may be variously embodied

and as the scope of such invention is to be determined as claimed.

I claim:

1. The combination of a plurality of rolls, 40 intermeshing gears carried by said rolls, a gear box enclosing the gears, and a flexible and yielding cover plate closing the gear box and apertured to receive the rolls.

2. The combination of a framework, a 45 plurality of bearings supported from said framework, a plurality of rolls having trunnions extending through the bearings, gears carried by said trunnions, a gear box enclosing said gears and having an open portion 50 presented towards said bearings, and a yielding and flexible plate apertured to receive the trunnions and covering the open portion of the gear box, said plate being located between said bearings and gear box. 55

3. The combination of a plurality of rolls having trunnions, a supporting member having a plurality of relatively movable bearings through which said trunnions project, means for adjusting the relative positions of 60 said bearings, a plurality of intermeshing gears carried by said trunnions, a gear box enclosing said gears and having an open side through which said trunnions extend, and a flexible and yielding plate apertured 65 to receive said trunnions and closing the open side of said gear box.

In testimony that I claim the foregoing I have hereunto set my hand at Milwaukee, 70 in the county of Milwaukee and State of Wisconsin.

AUGUST ROSENTHAL.
